CLAIM

The ornamental design for a one-piece multifunctional wearable blanket, as shown and described.

DESCRIPTION

FIG. 1 is a top front perspective view of the one-piece multifunctional wearable blanket showing my new design; FIG. 2 is a front elevation view thereof, with the rear elevation view being a mirror image thereof; FIG. 3 is a right elevation view thereof, with the left elevation view being a mirror image thereof; FIG. 4 is a top elevation view thereof; FIG. 5 is a bottom elevation view thereof; FIG. 6 is a top front perspective view thereof, shown in use worn around the waist; and, FIG. 7 is a top front perspective view thereof, shown in use worn above the shoulders. The broken lines in FIGS. 6 & 7 showing the one-piece multifunctional wearable blanket in use illustrates environment and forms no part of the claim.

1 Claim, 3 Drawing Sheets
